A. KRAGE.
CARPENTER'S SQUARE.
APPLICATION FILED MAR. 30, 1916.

Patented Dec. 12, 1916.

UNITED STATES PATENT OFFICE.

AUGUST KRAGE, OF HERMON, CALIFORNIA.

CARPENTER'S SQUARE

1,207,935.

Specification of Letters Patent. Patented Dec. 12, 1916.

Application filed March 30, 1916. Serial No. 87,664.

To all whom it may concern:

Be it known that I, AUGUST KRAGE, a citizen of the United States, residing at Hermon, in the county of Los Angeles and State 5 of California, have invented new and useful Improvements in Carpenters' Squares, of which the following is a specification.

This invention relates to an improved carpenter's square and contemplates an extension straight edge and improved means for securing said straight edge to one member of the square in alinement therewith and for readily disconnecting said straight edge from the square member as desired.

10 15 More particularly the invention comprises means for taking up wear of the engaging parts of the securing means of the square member and extension straight edge, so that the extension straight edge may be held rigid 20 to the square member when said parts become worn.

The invention is illustrated in the accompanying drawings which form a part of this specification, in which:

25 Figure 1 is a perspective view of the square and the extension straight edge secured to one member of the square. Fig. 2 is a sectional view of one member of the square and the extension straight edge secured thereto, taken on line x^2-x^2 of Fig. 1. Fig. 3 is a plan view of the under side of a portion of the square and extension straight edge secured to one of the square members as shown in Fig. 1, with said member broken away to 30 35 show the securing element for securing the extension straight edge to the square member. Fig. 4 is a cross section of one member of the square, with the extension straight edge secured thereto, taken on line x^4-x^4 of Fig. 3. Fig. 5 is a view of the securing 40 45 tongue of the extension member. Fig. 6 is a perspective view of the securing element for securing the extension straight edge to one of the square members.

45 The square comprises two members 1 and 2 arranged in the usual manner at right angles to each other, and an extension straight edge 3. The member 1 is hollow and open at one end to receive a securing 50 55 tongue 4 at one end of the extension straight edge 3. A shoulder 5 is formed at the junction of the end of said straight edge and said tongue, which shoulder is adapted to abut against the end of the square member 1, to limit the projection of said tongue within said member and to aline the extension

straight edge with said square member. The side edges of the tongue 4 are adapted to fit the inner surface of the side walls of the square member 1 to hold the extension 60 straight edge 3 rigidly in alinement with the side edges of the square member. The tongue 4 is provided with a T-shaped slot 6, extending longitudinally at 7 from the end of the tongue and transversely of the 65 tongue at 8.

Within the square member 1 is pivoted a securing element comprising a lever 10, the square member being provided with a slot 11 to receive the lever and permit swinging 70 movement thereof. Said lever comprises two members, an outer member 12 and an inner member 13, the outer member resting upon the inner member. Ears 15 are formed on the side edges of member 12 and extend 75 downwardly over the side edges of the member 13 and rest at the sides of a notch 16 formed in the under side of the lever member 13. A pivot pin 17 extends transversely through the solid parts 18 of the square 80 member 1 through the ears 15 and notch 16 of lever member 13, whereby the lever 10 is pivoted to the square member 1 within the slot 11 thereof. Set screws 19 extend into the parts 18 of square member 1 and engage 85 the pivot pin 17 to hold said pin in position in the square member. One end of the members of the lever 10 is enlarged, such enlargement of the member 12 forming a thumb 90 piece 20 to be engaged by the thumb of the user to depress said end of the lever. The enlargement of the inner lever member 13 is provided with a slot 21, extending longitudinally of the lever member, into which slot projects a lug 22 from the upper lever 95 member 12. A screw 25 extends through the end of the enlarged portion of the lever member 13 into the enlargement slot 21 and is swiveled to the lug 22 so that upon turning the screw, the lever member 13 is adjusted longitudinally with relation to the lever member 12, the notch 16 in the member 13 permitting the member to move over the pivot pin 17. On the end of the lever member 13, opposite the thumb piece 20, is 100 105 formed a latch 30, said latch being adapted to fit within the portion 8 of the slot 6 in the straight edge tongue 4, and the latch end of said lever member being adapted to fit within the portion 7 of said tongue slot, when said tongue extends within the square member 1, whereby the extension straight edge 3 is 110

secured to said square member, with the side edges of the tongue 4 in engagement with the inner side surfaces of the member 1 and the shoulder 5 of the straight edge 3, in engagement with the end edge of said square member, thus securing the straight edge rigidly to the square member in alinement therewith.

A flat spring 35 secured to the under side 10 of the square member 1 and counter-sunk flush with the surface of the under side of the square member, extends into a slot 36 in the lower wall of the square member and engages the enlarged end of the lever member 13 to hold the lever 10 in its normal position within the square member and the latch 30 15 in engagement with the slot portion 8 in the straight edge tongue 4. An embossment 37 is formed on the lower side of the enlarged 20 end of the lever member 13 below the screw 25 to strengthen the metal of said enlarged end around said screw, said embossment extending through a notch 38 in the end of spring 35, flush with the lower side of the 25 spring and flush with the lower side of the square member 1, when the lever 10 is in its normal position.

Any outward pull on the extension straight edge 3 will cause the latch 30 to engage the shoulders 40 at one side of the slot portion 8 and prevent the tongue 4 from being pulled 30 out of the square member 1, and the straight edge 3 from being disengaged from said square member.

The under side 41 of the latch 30 is beveled 35 so that when the tongue 4 is introduced into the member 1, said beveled under side will engage the end of the tongue at the sides of the slot portion 7, which will cause the lever 40 10 to swing on its pivot 17 and allow the end of the tongue to pass under the latch until the latch registers with the slot portion 8, whereupon the latch, under the influence of the spring 35 will snap into the slot 45 portion 8 and the latch end of the lever into the slot portion 7, and lock the extension straight edge to the square member 1 in proper alinement therewith.

Upon pressing the thumb piece 20 with 50 his thumb, the user may cause the lever 10 to swing on its pivot and disengage the latch from the shoulder 40 of the tongue, so that the straight edge may be withdrawn from the square member 1.

The pivot pin 7 engages the upper wall of the notch 16 whereby the lever-member 13 is held in position against the lever member 12. When the engaging edge of the latch 30 and the shoulders 40 of the straight edge 60 tongue 4 become worn, the wear may be taken up by turning the screw 25 so that the lever member 13 and latch 30 may be moved longitudinally with relation to the lever member 12 into such position that when the 65 straight edge shoulder 5 engages the end

edges of the square member 1 and the sides of the tongue 4 engage the inner surfaces of the sides of the square member, the latch will engage the tongue shoulders 40 and hold the straight edge rigidly to the square member 70 in alinement therewith, as before the wear of the parts took place.

The lever 10 may be removed from the square member 1 upon loosening the set screws 19 and removing the pivot pin 17 75 from the lever. The portion of the spring 35 engaging the end of the lever member 13 is enlarged so as to engage substantially the entire surface of the enlarged end of the lever member to apply the necessary spring 80 pressure to the lever 10.

The square members 1 and 2 and the extension straight edge may be provided with graduations for measuring, if desirable.

I claim:

1. In a carpenter's square, a pair of square members, an extension straight edge, shoulders on said straight edge, a securing element on one of said square members, said securing element comprising a pair of lever members, one of said lever members being pivoted to said square member, the other lever member being carried by said first lever member, a latch on said second lever member adapted to engage said shoulders on said 95 straight edge to lock said straight edge to said square member in alinement therewith, and means for adjusting said second lever member with relation to said first lever member to take up wear in said shoulders and 100 said latch.

2. In a carpenter's square, a pair of square members, an extension straight edge, shoulders on said straight edge, a securing element on one of said square members, said securing element comprising a pair of lever members, a pivot pin for pivoting one of said lever members to one of said square members, the other lever member being provided with a notch through which said pin 110 extends, said pin engaging the upper wall of said notch to hold the second lever member against said first lever member, a latch on said second lever member for engaging said shoulders to lock said straight edge to 115 said square member in alinement therewith and means for adjusting said second lever member to take up wear in said shoulders and said latch, said notch permitting such relative adjustment of said lever members. 120

3. In a carpenter's square, a pair of square members, an extension straight edge, shoulders on said straight edge, a securing element comprising a pair of lever members, one of said lever members being pivoted to 125 one of said square members, the other lever member being carried by said first lever member, a latch on said second lever member adapted to engage said shoulders on said straight edge to lock said straight edge to 130

one of said square members in alinement therewith, a lug on one of said lever members, a screw extending through a portion of the other lever member, said screw being swiveled to said lug so that upon turning said screw, said second lever member may be adjusted to take up wear in the latch and said shoulders.

4. In a carpenter's square, a pair of square members, an extension straight edge, shoulders on said straight edge, a securing element comprising a pair of lever members, one of said lever members being pivoted to one of said square members, the other lever member being carried by said first lever member, a latch on one end of said second lever member for engaging said shoulder to lock said straight edge to one of said square members to hold said straight edge in alinement with said square members, the other end of said second lever member being provided with a longitudinal slot, a lug projecting from said first lever member into said slot, a screw extending through the slot end of said lever member and swiveled to

said lug for adjusting said second lever member and latch to take up wear in said latch and said shoulders.

5. In a carpenter's square, a pair of square members, an extension straight edge, shoulders on said straight edge, a securing element in one of said square members, said securing element comprising a pair of lever members, a pivot pin in said square member for pivoting one of said lever members to said square member, set screws for holding said pivot pin in said square member, a latch on one end of the other lever member for engaging said shoulders to lock said straight edge to said square member in alinement therewith, a screw extending into the end of one of said lever members, a lug on the other lever member to which said screw is swiveled, said screw being adapted to adjust said latch lever member with relation to the other lever member to take up wear in said latch and said shoulders.

In testimony whereof I have signed my name to this specification.

AUGUST KRACE
